UNITED STATES PATENT OFFICE.

OCTAVIO CAVIGLIA, OF HABANA, CUBA.

MEASURING DEVICE.

No 853,768.

Specification of Letters Patent.

Patented May 14, 1907.

Application filed July 30, 1906. Serial No. 328,335.

To all whom it may concern:

Be it known that I, OCTAVIO CAVIGLIA, a subject of the King of Spain, and a resident of Habana, Cuba, have invented a new and Improved Measuring Device, of which the following is a full, clear, and exact description.

My invention relates to measuring devices adapted to hold a quantity of material and to discharge the same from a vessel in predetermined quantities, and while it is adapted to be used with materials of different kinds such as powdered soap and other material in granulated or powdered form, it is especially adapted to be used on the table for holding sugar and for delivering at each operation the desired amount for a cup of coffee or tea. One of the objects of my invention is to provide a device of this character which shall be entirely sanitary, and to dispense with the use of a general receptacle from which the material is removed by means of spoons.

Such objects I accomplish by the means illustrated in the drawings, in which drawings like characters of reference indicate like parts throughout the views, and in which

Figure 1 is a vertical elevation of a measuring device embodying my invention; Fig. 2 is a vertical transverse section of the same; and Fig. 3 is a plan of the lower portion of the device detached from the holding receptacle.

As illustrated in the drawings, 1 represents a receiver which may be made of any general construction, and provided with a top or cover 2. I prefer, however, to provide the top of the receptacle with a collar or flange 3 adapted to be closed by means of a cap or plug. The lower portion of the receiver is provided with an inclined bottom 4 having an aperture 5 formed therein and adapted to register with the compartments of a rotary measure located below the bottom 4 of the receiver. I prefer to attach the bottom 4 of the receiver to a cylindrical band 4^a corresponding with the inner diameter of the receiver and adapted to be inserted within such vessel. The band 4^a is cut away at its forward portion on the line 4^b which extends upward from the lower end of the band 4^a, then transversely of said band, and downward again to the end of the band forming a curved arch in front elevation, and a semi-arch in side elevation, as shown in Fig. 2.

The rotary measure is constructed of a series of blades 7 extending in radial lines and

connected together at their inner ends by means of a hub 8 which is mounted upon a vertical pin 9, and they are also connected together between their ends by means of curved plates 10 preferably extending in a circular line transversely of the blades 7. The measure is provided with a ratchet of any suitable construction, preferably formed by notching the upper wall of the transverse partitions 10 so as to form a series of teeth 10^a equal in number to the compartments of the measure.

A lever 11 is mounted upon the pin 9 on which the measure is journaled and a pawl 12 is pivoted on said lever and so arranged that its end engages the ratchet teeth 10^a formed on the measure.

The measure is arranged within a chamber composed of a cylindrical band 6 detachably secured to the shell 1 of the receiving chamber, and is provided with a bottom 6^a having an aperture 13 which is adapted to register with the compartments of the measure, and a discharge spout 14 is secured to the lower portion of the vessel so as to cover the discharge opening 13 in the measuring chamber. This spout 14 preferably extends diagonally outward from the bottom 15 of the vessel.

A connecting rod 16 is pivoted at one end to the ratchet lever 11 mounted upon the central pivot pin 9, and the opposite end of such rod is pivotally connected with a lid 17 hinged to the outer end of the spout 14. This end of the connecting rod is off-set so as to engage an arm 17^a secured to the lid 17 of the spout 14, the arm being preferably provided with a slot 17^b adapted to allow the end of the lever 16 to be detached therefrom. The outer end 11^a of the lever 11 extends through the shell of the receiver 1 by means of which and the pawl 12 attached to said lever the rotary measure may be moved to the extent of one of its compartments by a single movement of the ratchet lever.

A thumb piece 18 is attached to the outer portion of the receiver so as to enable the ratchet lever to be readily operated. A spiral spring 19 is connected with the ratchet lever, and also with the receiver so as to draw the lever backward into its former position after pressure has been released therefrom. The pawl 12 is then in position to move the next compartment in line with the discharge orifice 13 by repeating the movement of the ratchet lever. A slot 20 is made

in the cylinder of the receiver adapted to permit the ratchet lever to travel in its path, and a shield 21 indicated by dotted lines in Fig. 1 is secured to the end of the lever 11 so as to bear against the slot of the receiver and prevent foreign matter from entering the receiver through such slot as shown in Fig. 3.

In the construction shown herein I have embodied my device in its preferred form. 10 I do not desire to be limited to the specific construction of the elements as shown and described herein, however, as other means having similar capabilities may be employed without departing from my invention.

15 Having thus described my invention, what I claim as new and desire to secure by Letters Patent is:

1. The combination with a receiving chamber having an inclined bottom provided 20 with a segmental opening at its outer portion, of an outlet chamber provided with a discharge opening spaced apart from the opening of the receiving chamber, and a rotary measure having a series of compartments adapted to register with the openings of the receiving and discharge chambers, substantially as shown and described.

2. The combination with a receiving chamber having an inclined bottom provided 30 with a segmental opening at its outer portion and secured to a cylindrical band adapted to engage the end of the receiving chamber and to be detached therefrom, of an outlet chamber detachably secured to the receiving chamber and provided with a discharge opening spaced apart from the opening of the receiving chamber, and a rotary measure having a series of compartments adapted to register with the openings of the receiving and discharge chambers, substantially as shown and described.

3. The combination with a receiving chamber having an inclined bottom provided 45 with a segmental opening at its outer portion and secured to a cylindrical band detachably secured to the receiving chamber and cut away circumferentially on one side, of an outlet chamber provided with a discharge opening spaced apart from the opening of the receiving chamber, a rotary meas-

ure having a series of compartments adapted to register with the openings of the receiving and discharge chambers, and a series of ratchet teeth corresponding with said compartments and a reciprocating lever adapted 55 to engage said teeth and rotate said measure in step-like manner, substantially as shown and described.

4. The combination with a receiving chamber and a measuring chamber, each 60 provided with a discharge aperture, of a spout connected with the discharge aperture of the measuring chamber, a lid hinged to said spout, a reciprocating lever, a rod connecting the end of said lever and lid of said 65 spout, a rotary measure having a series of compartments adapted to register with the aperture of said measuring chamber, and means for imparting a rotary motion to said measure, substantially as shown and described.

5. The combination with a receiving chamber having an inclined bottom provided 75 with a segmental opening at its outer portion and secured to a cylindrical band adapted to detachably engage the end of said receiving chamber and cut away circumferentially on one side, of an outlet chamber detachably secured to said receiving chamber and provided with a discharge opening 80 spaced apart from the opening of the receiving chamber, a rotary measure having a series of compartments adapted to register with the openings of the receiving and discharge chambers, and a series of ratchet 85 teeth corresponding with the compartments of said measure, a reciprocating lever adapted to engage said teeth progressively, a discharge spout secured to the outlet chamber, and a lid adapted to close said spout and 90 connected with said lever, substantially as shown and described.

In testimony whereof I have signed my name to this specification in the presence of two subscribing witnesses.

OCTAVIO CAVIGLIA.
